UNITED STATES PATENT OFFICE.

JOHN VAL. KLEIN, OF RENVILLE, MINNESOTA.

RAT-TRAP.

1,277,949.

Specification of Letters Patent. Patented Sept. 3, 1918.

Application filed June 21, 1918. Serial No. 241,182.

To all whom it may concern:

Be it known that I, JOHN VAL. KLEIN, a citizen of the United States, residing at Renville, in the county of Renville and State 5 of Minnesota, have invented a new and useful Rat-Trap, of which the following is a specification.

This invention relates to rat traps particularly designed for use in grain elevators, 10 etc., although it is also capable of use in any place where rodents are to be trapped. One of the objects of the invention is to provide a trap having a main receiving compartment to which one or more runways lead, there being 15 a novel arrangement of traps for directing the rodents from the runways into the compartment where they will be held until removed.

Another object is to provide runways 20 which can be readily attached to and removed from the walls of the receiving compartment and which, when in active positions, serve to hold the door or doors of said compartment so that the rodents cannot be 25 removed accidentally or otherwise.

With the foregoing and other objects in view which will appear as the description proceeds, the invention consists of certain 30 novel details of construction and combinations of parts which will be hereinafter more fully described and pointed out in the claims, it being understood that various changes may be made in the construction and arrangement of the parts without de- 35 parting from the spirit or sacrificing any of the advantages of the invention as set forth in the appended claim.

In the accompanying drawings the preferred form of the invention has been shown.

40 In said drawings

Figure 1 is a plan view of the trap, parts being shown in section.

Fig. 2 is an enlarged section on line 2—2, Fig. 1.

45 Fig. 3 is a side elevation, a portion being shown in section.

Fig. 4 is an end elevation.

Referring to the figures by characters of 50 reference, 1 designates a cage like receptacle the top of which is preferably solid while the sides are formed of bars, as shown, there being a door 2 at one or both sides which can be fastened in closed positions by any

suitable means, indicated generally at 3. An extension 4 is provided at each end of 55 the receptacle and has a bottom 5 inclined downwardly toward the receptacle, there being a fixed partition 6 between the upper portion of the receptacle and each extension and a hinged door 7 suspended from each 60 partition for normally closing communication between the extension and the receptacle. These doors are adapted to swing inwardly into the receptacle when moved to open positions and arms 8 having weights 65 9 and connected to the doors 7 serve to hold the doors normally closed. These arms extend through the walls of the receptacle, there being openings 10 provided therefor.

Hingedly mounted within each extension 70 4 is a trap door 11 adapted to swing downwardly onto the inclined bottom 5 but normally held elevated and in line with the top of the door 7 by an arm 12 connected to the trap door and provided with a weight 13. 75 A compartment is thus formed in each extension above the trap door, this compartment having an inlet 14 at one side. The top of the receptacle 1 is extended over the compartments and doors 15 are provided 80 therein over the compartments to give access thereto when desired.

Secured along one side of each extension 4 below and outside the inlet 14 thereof is a flange 16 having a slot 17 therein. Pins 18 85 extend upwardly from the top of each extension directly over the inlet 14 thereof.

Arranged at each side of the receptacle 1 is a runway or incline 19 in the form of an elongated box having a central, longitudinal, vertical partition 20 forming two passages within the incline. The lower end of each incline, which is open, is adapted to rest on the floor and to be secured to the side of receptacle 1 in any suitable manner, as 90 by means of hooks 21. The upper end of the incline has a lateral outlet 22 adapted to register with the inlet 14 and overhung by a flange 23. This flange is adapted to rest on the extension 4 and has openings 24 95 for the reception of the pins 18. Studs 25 extend downwardly from the bottom of the outlet portion of the incline and are adapted to extend into the slot 17, thus to hold the incline secured to the receptacle 1. The 100 inclines, when in position, are adapted to

extend across the doors 2, thus to prevent them from being opened accidentally or otherwise without removing the inclines.

When bait is placed in the receptacle, the 5 rodents will crawl up the inclines 19 and pass through the outlets 22 in the inclines to the receptacles above the trap doors 11. As soon as the weight of one or more rodents is applied to a trap door, the door will swing 10 downwardly, causing the rodent to fall against the door 7 which will thus swing open and then closed, leaving the rodent locked in the receptacle 1. The herein described trap can be made of very large capacity and four rodents can be discharged thereinto at one time, thus rendering the trap particularly desirable for use in grain elevators and other places where they are 15 found in large numbers.

20 The hooks 21 can not only be provided at the lower ends of the inclines for fastening

them to the receptacle 1, but they can also be arranged at the upper ends thereof.

What is claimed is:—

A trap including a receptacle having a 25 side door, an extension at one end of the receptacle provided with an inlet, upstanding connecting pins upon the extension, a slotted flange on said extension, an incline at one side of the receptacle and extending 30 across the door to prevent opening thereof, said incline opening into the inlet of the extension, and separate means on the incline for engaging the pins and flange respectively.

In testimony that I claim the foregoing as my own I have hereto affixed my signature in the presence of two witnesses.

JOHN VAL. KLEIN.
